TABLET DISPENSER

Robert Bedaux, Paris, France

Application October 23, 1948, Serial No. 56,112
In France April 2, 1948

12 Claims. (Cl. 206—42)

1

This invention relates to dispensers and more particularly to a container and dispenser of tablets of either a pharmaceutical or confectionary nature or the like.

The article of the present invention comprises a compact, generally cylindrical container which may be carried about in either a pocket or a purse and which is effective in dispensing individual tablets as required.

A quantity of stacked tablets, generally circular in form, are maintained in the dispenser which is formed with a discharge outlet for dispensing single tablets. In order to avoid uncertainty or haphazard operation of the device, each tablet is ejected by a positive pushing action at the same time that the discharge outlet is uncovered. Thus, it is unnecessary to shake or otherwise agitate the dispenser thereby avoiding ejection of more than the required tablets and affording smooth and effective operation.

The detailed operation of the dispenser as well as the objects of the instant invention will be further understood from the following description and drawings, in which

Fig. 1 is an elevational view of the dispenser;

Fig. 2 is a disassembled view thereof;

Fig. 3 is a section along the lines 3—3 of Fig. 2.

Fig. 4 is a section along the lines 4—4 of Fig. 2.

Fig. 5 is a section along the lines 5—5 of Fig. 1.

The dispenser comprises a hollow, cylindrical, elongated body 10 which may be fabricated of metal, plastic or any other suitable material. Stacked within the body 10 is a plurality of individual tablets 11 which are indicated as being circular in the manner of aspirin tablets or certain vitamin pills. Body 10 is formed with a neck 12 designed to engage the cap 13 when the dispenser is in closed condition. Integral with neck 12 is the extending arc 14 which, in the form shown, occupies about 160 degrees of a circle. Secured to the inner wall of arc 14 is the tongue or arm 15 which serves as the ejector for individual tablets.

Tongue 15 is connected, as by solder or the like, at its end 16 to arc 14. The other end 17 is therefore free. Tongue 15 is preferably, but not necessarily, fabricated of a resilient, flexible metal such as thin spring steel of a normal curvature which is greater than the curvature of the cylindrical body 10. Accordingly, the tongue 15, and particularly its free end 17, tend to remain inwardly in respect to the inner periphery of body 10 as illustrated in Fig. 3.

Cap 13 is formed with a lateral discharge outlet 20 which, in the form shown, occupies slightly

less than 180 degrees of the circular formation of the cap. The floor of the cap supports a platform 21 upon which rest the tablets. Platform 21 is circular and of lesser diameter than that of the cap 13 so as to form an annular slot 22 between the platform 21 and the cylindrical wall of the cap. Platform 21 is further formed with a somewhat arcuate slot 23 extending to the floor of the cap and from the edge to the center of the platform. The thickness of platform 21 is less than the height of tongue 15 for purposes which will be hereinafter made clear.

When the cap 13 is applied over the neck 12, both the arc 14 and tongue 15 enter the annular slot or groove 22 so as to permit complete engagement of the cap by the neck 12. It may be found, in some instances, that in order to secure such engagement, the cap should be turned until these parts fall into a natural engaging position, such position being insured when the tongue 15 is in the region of arcuate slot 23. Inasmuch as tongue 15 is of greater height than the width of platform 21, it will extend over slot 23 to a height which is arranged to be approximately 25 the width of the tablet to be dispensed.

Arc 14 forms the closure for discharge outlet 20 in the closed position of the container. When the body 10 is rotated with respect to cap 13 (for example, in a clockwise direction) the arc 14 will ride in the slot or groove 22 until it uncovers the discharge outlet 20. At the same time, the free end 17 of tongue 15, being inwardly biased, will enter arcuate slot 23 and, guided by the wall 24 thereof, will ride into the slot and will be further biased away from arc 14. When the body is rotated in a reverse direction, the tongue 15 will leave the slot 23 at the same time that the extension comes around and closes the discharge outlet. That portion of the groove 22 which admits only the arc 14 may be formed slightly narrower than the remainder so that the tongue, when being rotated, can only enter the slot 23.

The instant invention is practiced as follows: Body 10 is filled with a quantity of tablets 11 as illustrated by the dotted lines of Fig. 1. Cap 13 is then applied and engaged by neck 12, the arc 14 entering the annular slot or groove 22. By rotating the cap slightly, the engagement may be properly effected. The dispenser is held in the vertical position illustrated in Fig. 1, and the body 10 rotated in a clockwise direction. The cap, of course, may be rotated in a counter-clockwise direction instead, only relative rotation being necessary. As the body 10 rotates, the arc 14 which normally covers the discharge out-

let 20, rides around the slot 22 so as to expose the discharge opening and the lowermost tablet 11a. As the slot becomes completely exposed so as to permit the exit of the tablet, the tongue 15 rides around the arcuate slot 23 as illustrated in Fig. 5. The slot 23 is radial in that it extends generally along a radius of the circular platform 21. The tongue 15 being higher than the slot, pushes against the tablet 11a as illustrated in said Fig. 5 and forces it through the discharge opening. The tablet may be then easily removed by the fingers, while the next succeeding tablet is retained by the upper edge of tongue 15. The body 10 is then rotated in a reverse direction so that the tongue 15 is caused to leave slot 23 while arc 14 closes the discharge opening. Such next succeeding tablet thereupon drops into position on platform 21 and the operation may be repeated.

If it is desired to limit counter-clockwise movement of the body, a protuberance 25 may be formed in the slot 22 so that the leading edge of arc 14 will strike such protuberance 25 when the discharge opening is completely covered. Accordingly, the body 10 will have two limits of rotational movement. The first limit is effected by the stop action of slot 23 on enclosed tongue 15 in the open position of the discharge outlet, and the second limit is effected by the stop action of the protuberance 25 on the leading edge of arc 14 in the closed position of the discharge outlet.

It can be seen from the foregoing that a dispenser has been provided which can eject only one tablet at a time and wherein such ejection is automatic and accompanies the opening of the normally closed discharge outlet. Agitation of the dispenser is unnecessary and the discharge of the tablets is effected singly as required.

While there has been described what at present is considered a preferred embodiment of the invention, it will be evident that many changes and modifications may be made therein without departing from its spirit. It is therefore aimed in the appended claims to cover all such changes and modifications which fall within the true spirit and scope of the invention.

What is claimed is:

1. A dispenser for tablets comprising a hollow, elongated body adapted to contain a stacked pile of tablets, a cap rotatably engaged by said body and enclosing one end thereof, said cap being formed with a lateral discharge opening for ejecting individual tablets, a platform on the floor of said cap, said cap being formed with an annular groove between said platform and the wall of said cap, an arcuate extension on said body receivable in said annular groove for normally closing said discharge opening, and a pusher member connected to said arcuate extension and actuated by relative rotation between said body and said cap for forcibly ejecting tablets through said discharge opening.

2. A dispenser according to claim 1 and wherein in said platform is formed with a radial slot communicating with said annular groove, said pusher member being adapted to ride in said radial slot while said extension rides in said annular groove during exposure of said discharge opening and ejection of a tablet therethrough.

3. A dispenser according to claim 2 and wherein in said pusher member comprises a thin metallic spring arm connected at one end thereof to an inner wall of said arcuate extension, the other end thereof being free and biased inwardly in respect to said arcuate extension.

4. A dispenser for tablets comprising a hollow, elongated, cylindrical body adapted to contain a stacked pile of circular tablets, a cap rotatably engaged by said body and enclosing one end thereof, said cap being formed with a lateral discharge opening for ejecting individual tablets and having an annular groove formed at the closed end thereof and adjacent its inside wall, said cap having further formed thereon an arcuate, substantially radial slot adjacent the floor thereof, an arcuate extension on said body receivable in said annular groove for normally closing said discharge opening, and a thin spring arm connected at one end thereof to an inner wall of said arcuate extension, the other end thereof being free and biased inwardly in respect to said arcuate extension, both said arcuate extension and said spring arm being receivable in said annular groove and said spring arm being further receivable in said arcuate slot during relative rotation of said body and cap.

5. A dispenser according to claim 4 and including a circular platform formed on the floor of said cap, said annular groove being formed between said platform and the inner wall of said cap, and said arcuate slot being substantially formed along a radius of said platform.

6. A dispenser for tablets comprising a hollow, cylindrical, elongated body adapted to contain a stacked pile of circular tablets, a cylindrical cap rotatably engaged by said body and enclosing one end thereof, said cap being formed with a lateral discharge opening for ejecting individual tablets, a circular platform on the floor of said cap, said platform being of lesser diameter than the floor of said cap and forming an annular groove between itself and the cylindrical wall of said cap, said platform being further formed with an arcuate, substantially radial slot communicating with said annular groove, an arcuate extension on said body receivable and rotatable in said annular groove for normally closing said discharge opening, and a spring arm pusher member connected at one end thereof to said arcuate extension and having the other end thereof free and biased inwardly in respect to said arcuate extension, said spring arm being receivable in said annular groove together with said arcuate extension and being guided into said arcuate slot by relative rotation between said body and said cap so that the free end of said spring arm is caused to travel inwardly toward the center of said platform, said inward travel of said free end being operative to push a tablet through said discharge opening.

7. A dispenser according to claim 6 and wherein in said spring arm is of a greater height than said arcuate slot whereby a portion thereof extends above said arcuate slot for bearing against and discharging a tablet.

8. A dispenser according to claim 7 and wherein in said spring arm enters said arcuate slot at substantially the same time as said arcuate extension exposes said discharge opening.

9. A dispenser according to claim 8 and including stop means at both limits of travel of said arcuate extension and spring arm during both open and closed positions of said discharge opening.

10. A dispenser for tablets comprising a hollow, elongated body, an end member on said body, said end member being formed with a lateral discharge opening for ejecting individual tablets from a stacked pile thereof contained in said body, said end member being rotatably engaged

by said body and enclosing one end thereof, a spring arm pusher member connected to said end member so as to be actuated by relative rotation between said body and said end member, and means to guide said spring arm member radially inwardly during such relative rotation so as to effect contact with the lowermost of said stacked pile of tablets so as to forcibly eject said lowermost tablet through said discharge opening.

11. A dispenser according to claim 10 and wherein said means include a platform at one end of said dispenser and spaced from the body of the dispenser by an annular groove, said spring arm pusher member being receivable in said annular groove so as to be guided thereby and riding therein during said relative rotation.

12. A dispenser according to claim 11 and wherein said platform is formed with a radial

slot communicating with said annular groove, said pusher member being adapted to enter said slot after riding in said groove, the entrance of said pusher member into said slot effecting a discharge of the lowermost tablet through said discharge opening.
